O. JOHNSON.
AMUSEMENT DEVICE.
APPLICATION FILED APR. 10, 1920.

1,359,508.

Patented Nov. 23, 1920.

UNITED STATES PATENT OFFICE.

OWEN JOHNSON, OF NEW YORK, N. Y.

AMUSEMENT DEVICE.

1,359,508.

Specification of Letters Patent. Patented Nov. 23, 1920.

Application filed April 10, 1920. Serial No. 372,909.

To all whom it may concern:

Be it known that I, OWEN JOHNSON, a citizen of the United States, residing at New York, in the county of New York and State of New York, have invented certain new and useful Improvements in Amusement Devices, of which the following is a full, clear, and exact description, such as will enable others skilled in the art to which it appertains to make and use the same.

This invention relates to amusement devices, and more particularly to amusement devices embodying some of the features of a roller-coaster.

It is an object of the invention to provide an unusual and entertaining form of amusement device, which will excite interest in both spectators and participants.

It is a further object to provide an improved amusement device comprising features of structural superiority and functional advantage.

Other objects will be in part noted herein-after in connection with the following description of the accompanying drawing, which illustrates a typical embodiment of the invention, and wherein—

Figure 1 is a perspective view of the device; and

Fig. 2 is a side view of a car and a deflecting post.

In general, the device consists of an inclined plane upon which cars are projected, as by an elevated runway, having disposed at intervals on its surface holes or pockets through which the cars may drop in their courses, and having beneath its surface passage-ways leading from such pockets, communicating with exit gates at the lower edge of the surface.

Referring now more particularly to the drawing, there is shown a tower 1 containing an elevator for raising the cars to the starting point 2. An inclined runway 3 may be employed to convey the cars from the starting point 2 toward and upon the surface 4 of the inclined plane, and to afford initial impulse to the cars as they are projected upon the inclined plane adjacent its upper edge. The inclined plane may be divided into squares or rectangles, a plurality of which form pockets 5 leading to passage-ways beneath the surface. These passage-ways 6, as indicated by dotted lines in the drawing, may be circuitous and intercommunicating in form, and lead beneath the

surface to exit gates 7 adjacent the lower edge of the inclined plane. If desired, each passage-way may be so constructed as to constitute a separate unit, so that the entrance of a car through a particular pocket will insure emergence from a corresponding exit gate below.

A guard rail or fence 8 is disposed along the edges of the running surface, and in the present instance, this guard rail curves inwardly toward the lower end of the apparatus to guide any cars which may have failed to leave the surface through the pockets 5 out through a central exit 9 leading directly from the surface at its lower end. A further curved guide rail or fence 10 may be employed beyond the exists to guide the cars after their discharge toward the foot of the tower 1 and thus facilitate a second start. Posts or pins 11 are preferably disposed at intervals upon the surface to deflect the cars in case it is discovered that sufficient element of chance does not enter into the course of the car upon the running surface. These posts 11 may be removable and sufficient holes for receiving them, as for example, one at each corner of the squares, may be disposed on the surface so that the positions of the posts may be altered at will to prevent continuing definite courses being worn by the cars. The cars 12 may take any shape or form desired, but are preferably so constructed as to be able to ride in any direction in relation to their horizontal axes. For this purpose the wheels 13 of the car are preferably of caster construction to allow rotation of their attaching means.

A supplementary starting tower might be added adjacent the other lower corner of the plane, and the elevators are preferably of a size to accommodate more than one car, so that a plurality of cars may be running on the surface at one time. Further elements of chance may be gained by the employment of additional variously positioned starting points.

The device is designed particularly for use in amusement parks, etc., where crowds may be attracted and substantial revenue received by its operation.

In the present embodiment the cars are adapted to carry one or more passengers, who enjoy the double suspense afforded by a fast and exciting descent and by the uncertainty of the course which a given car may take. The entire running surface of the in-

clined plane is visible to spectators standing beyond the lower edge of the plane, and this surface may be divided into differently colored squares in the form of a checker-board, 5 thus adding to the attractiveness of the device and affording additional interest to those attempting to prophesy the course of a given car. In operation, the spectators or participants are invited to predict the 10 course of the car, and suitable prizes may be given to those who succeed. It will be evident that many varied opportunities are provided for such preselection. For example, it may be predicted that a certain car will 15 leave the surface through one of the pockets having a certain color, or the said pockets may be numbered and the number of the exit pocket predicted. Further, the point of final exit may constitute one of the 20 chances. For the latter purpose, the exit gates 7 may be numbered, as illustrated, and the numbers preselected or predicted in distinction from a discharge through the central opening 9.

25 As many changes might be made in the construction as shown and many widely different embodiments of the invention might be made without departing from the scope thereof or sacrificing its advantages, it is intended that all matter contained in the 30 above description or shown in the accompanying drawings be interpreted as illustrative and not in a limiting sense. It is also to be understood that the language used in 35 the following claims is intended to cover all the generic and specific features of the invention.

Having described my invention what I 40 claim as new and desire to secure by Letters Patent is:

1. In an amusement device, in combination, a plurality of gravity-propelled cars, a surface for said cars comprising an inclined plane, a plurality of exit openings 45 for said cars spaced at intervals over said surface, a supplementary discharge opening leading from the surface adjacent the lower edge thereof, means for elevating said cars and means for projecting said cars on said plane adjacent the higher portion thereof.

2. In an amusement device, in combination, an inclined plane, means to project cars upon the surface of said plane, comprising an inclined runway having its lower end 55 adjacent the higher end of the inclined plane, means to elevate cars for starting, exit openings at spaced points through said plane, discharge openings adjacent the lower edge of said plane, and communicating passages 60 from said exit openings to said discharge openings.

3. In an amusement device, in combination, an inclined plane, a runway having an elevated starting end, a vertical tower adjacent the starting end of the runway and

the lower edge of the plane, exit openings on the surface of said plane, discharge openings adjacent the lower edge of said plane, means to guide the cars from said discharge openings toward the base of the tower and an elevator to raise the cars to the starting point. 70

4. In an amusement device, in combination, an inclined plane, means to project cars on the surface thereof adjacent the higher edge of said plane, exit openings so spaced 75 at intervals over the surface of said plane as to receive said cars under normal conditions before said cars reach the lower part of said surface, passage-ways leading therefrom beneath the surface of said plane, said 80 passage-ways having discharge openings adjacent the lower edge of said plane.

5. In an amusement device, in combination, an inclined plane, means to project cars upon the surface of said plane comprising 85 an inclined runway having its lower end adjacent the higher portion of said plane, means to elevate cars to the starting point, receiving openings for the cars spaced at intervals over the surface of said plane, passage-ways beneath said surface, said 90 passage-ways having discharge openings adjacent the lower edge of said plane.

6. In an amusement device, in combination, an inclined plane, means to project 95 cars on the surface of said plane adjacent its higher edge, receiving pockets for said cars spaced at intervals over the surface of said plane, circuitous intercommunicating passage-ways leading from said pockets 100 beneath the surface of said plane, said passage-ways having discharge openings adjacent the lower edge of said plane.

7. In an amusement device, in combination, an inclined plane, means to project 105 cars on the surface of said plane adjacent its upper edge, receiving pockets for said cars so spaced at intervals over the surface of said plane as to receive said cars under normal conditions before said cars reach the 110 lower part of said surface, bumper posts adjustably disposed over the surface of said plane, passage-ways beneath the surface leading from said receiving pockets, said 115 passage-ways having discharge openings adjacent the lower edge of said plane.

8. In an amusement device, in combination, an inclined plane, means to project cars on the surface of said plane adjacent its upper edge, receiving pockets for said 120 cars spaced at intervals over said surface, passage-ways beneath said surface leading therefrom, discharge openings from said 125 passage-ways adjacent the lower edge of said plane, a supplementary central discharge opening leading from the surface of said plane adjacent its lower edge, and means to guide cars approaching said lower edge through said central opening.

9. In an amusement device, in combina- 130

- tion, an inclined plane having a checker-board surface, means to project cars upon said surface adjacent its upper edge, a plurality of divisions of the checker-board forming receiving pockets for cars, passage-ways leading from said receiving pockets beneath the surface of said plane, said passage-ways having discharge openings adjacent the lower edge of said plane.
- 10 10. In an amusement device, in combination, an inclined plane, means to project cars on the surface of said plane adjacent its upper edge, passage-ways beneath the surface of said plane, pockets in said inclined plane to allow egress for cars through said
- 5 passage-ways, said pockets having distinguishing markings, exit openings for said passage-ways adjacent the lower edge of the plane, said exit openings having distinguishing markings, and one or more discharge openings for cars approaching the lower edge of said plane upon the surface thereof. 20
- In testimony whereof I affix my signature, in the presence of two witnesses.

OWEN JOHNSON.
